UNITED STATES PATENT OFFICE.

EMIL GUTMANN, OF NEW YORK, N. Y.

GARTER.

SPECIFICATION forming part of Letters Patent No. 717,844, dated January 6, 1903.

Application filed August 30, 1899. Serial No. 728,955. (No model.)

To all whom it may concern:

Be it known that I, EMIL GUTMANN, a citizen of the United States, and a resident of the borough of Manhattan, in the city and State of New York, have invented a new and useful Improvement in Garters, of which the following is a specification.

My invention relates to an improvement in garters, with the object in view of increasing their durability and rendering their action easy and agreeable to the wearer. To this end I omit rubber elastic entirely, as it is well known that rubber loses its elasticity by age and that it becomes useless much more rapidly in hot countries or where it is in close proximity to the body of the wearer than where it is kept cool and dry. At the same time I propose to retain the web feature and to provide sufficient elasticity by a metallic spring alone interposed between web-sections and of such structure that it will not press unduly upon the limb of the wearer at any one point.

A practical embodiment of my invention is represented in the accompanying drawings, in which—

Figure 1 is a plan view of the garter. Fig. 2 is an edge view, and Fig. 3 is a section through the yielding portion from front to rear.

As at present constructed the body of the garter is composed of two web-sections and one metallic elastic section, the two web-sections being denoted by A and A' and the metallic section by B. From the end of one of the web-sections a loop C extends, as is common, and is provided with a clasp for engaging the stocking, while the free end of the opposite web-section A' is provided with a hook a to catch one of the parts of the cord-loop

C in adjusting the garter to the limb, as is common. The web-section A is further provided with a cramp-clasp D, as is common, for adjusting the length of the garter and the ends of the web-section adjacent to the yielding spring-section B are folded over and retained in their folded-over position by means of cramp-clasps d d' of well-known or approved form. This folding over of the adjacent ends of the web-sections forms a neat smooth finish at the ends and at the same time provides bights a' a' at the ends of the web-sections for the reception of the ends of the wire

which is utilized to form the spring-section B. The spring-section B is preferably formed by a highly elastic wire b, which is passed zig-zag back and forth from edge to edge of the band of the spring portion B and given one or more turns b' at each edge before passing to the opposite edge, the result being when viewed in elevation a series of eyes at the turns b' at each opposite edge of the spring portion, the wire intermediate of said lines of eyes extending diagonally back and forth, each succeeding strand crossing the preceding, thereby affording a comparatively flat broad bearing, so that this spring portion will rest easily against the limb of the wearer, the crossings of the wire intermediate of the eye portions at the edge forming a series of retaining-points which serve well the purpose of preventing the garter from slipping down. The opposite ends of the wire which forms the spring portion are passed through the bights in the ends of the web-sections A A', and to prevent them from wearing the bights the adjacent edges of the cramp-clasps d d' are turned over, as shown at d', along the inner edge of the bight in the web-forming sockets for retaining the wire B and preventing the wire B from chafing against the web. The spring-section thus formed yields readily to accommodate itself to the motions of the limb of the wearer, is cool, and is not affected by heat or age, but retains its elasticity during the life of the web portion of the garter.

It is obvious that changes might be resorted to in the form and arrangement of the several parts described. Hence I do not wish to limit myself strictly to the structure herein shown; but

What I claim is—

A garter comprising non-elastic web-sections and an interposed metallic spring-section formed by wire arranged in zigzag form and coiled at the opposite edges of the section, producing a flat spring-band which forms a substantial continuation of the flat web-sections, metallic clasps located at the adjacent ends of the web-sections and provided with sockets for the reception of the ends of the wire which forms the spring-section, the non-elastic web-sections being located in position to engage the front and sides of the leg and the interposed metallic spring-section in

position to engage the back portion of the leg, and means at the free ends of the web-sections for engaging a stocking and holding the garter in position, substantially as set forth.

In testimony that I claim the foregoing as my invention I have signed my name, in pres-

ence of two witnesses, this 25th day of August, 1899.

EMIL GUTMANN.
